UNITED STATES PATENT OFFICE.

FREDERICK V. PEPPER, OF LOS ANGELES, CALIFORNIA.

WASHING-MACHINE.

992,048.

Specification of Letters Patent.

Patented May 9, 1911.

Application filed May 5, 1910. Serial No. 559,591.

To all whom it may concern:

Be it known that I, FREDERICK V. PEPPER, a citizen of the United States, residing in the city of Los Angeles, county of Los Angeles, State of California, have invented new and useful Improvements in Washing-Machines, of which the following is a specification.

My invention relates to that type of washing machines in which the clothes are washed by means of vertically reciprocating pounders operating in a clothes receptacle; and the object thereof is to provide a simple and efficient device, in which the clothes 10 pounders are automatically shifted from point to point in the clothes receptacle and to provide a pounder of high efficiency. I 15 accomplish these objects by the machine described herein and illustrated in the accompanying drawing, in which—

Figure 1 is a side elevation partly in section of my improved machine. Fig. 2 is an enlarged detail partly in central section of the pounder. Figs. 3 and 4 are enlarged 25 detail views to illustrate the connection between crank wheel 33 and wrist pin 37. Fig. 5 is an enlarged detail showing a connection of arm 16 with arm 15 and some of the adjacent parts.

30 In the drawings 5 is the base frame in the center of which is rigidly secured a tubular bearing 6. In the bearing is mounted a shaft 7 upon the upper end of which is secured a spider 8. Upon the outer ends of 35 this spider is secured an annular ring 9 provided with an internally projecting flange 10, upon which flange the tub or clothes receptacle 11 is placed when the machine is in position for use. This ring is supported 40 by rollers 12 revolvably mounted on the base frame. Below bearing 6 and secured to shaft 7 is a ratchet wheel 13 which is adapted to be engaged by dog 14, which dog is mounted upon arm 15 revolvably mounted 45 upon the lower end of shaft 7. To arm 15 is secured a pitman 16 having a knuckle joint 17 therein. Bolt 15^a which secures dog 14 to arm 15, also secures pitman 16 to arm 15. This pitman is pivotally secured to the 50 lower end of lever 18, which is pivoted at 19 in bearings 20 secured to shank 21 of the upper frame 22. Shank 21 has a slot 23 extending therethrough, through which slot bolts 24 pass, whereby the shank is adjustably secured to the top of leg 25 of the base 55 frame. Bolts 24 also pass through holes in

the top of this leg. The upper frame is U-shaped, and the outer ends terminate in bearings 26 in which is revolvably mounted a hollow shaft 27, on the outer end of which is secured an operating wheel 28 which is provided with a handle 29. Within the hollow shaft is another shaft 30 which is provided with a pin 31 that projects through a slot 32 in the hollow shaft and keeps the two shafts from separating and causes the inner shaft to rotate with the outer one when the outer shaft is rotated. Upon the outer end of shaft 30 is secured a crank wheel 33 which has an eccentric 70 cam groove 33^a in the face thereof. Shaft 30 passes through and is revolvble in vertical pounder frame 34, which has arms provided with bearings 35 at the top and bottom thereof. In these bearings is mounted 75 a pounder shaft 36, to which is secured wrist pin 37 between said bearings, which pin enters the cam groove 33^a of the crank wheel to reciprocate the pounder shaft vertically. The upper frame carries an arm 38 in which 80 is revolvably mounted a shaft 39 on the upper end of which is a beveled pinion 40. This pinion meshes with a mutilated gear 41 secured upon hollow shaft 27. Shaft 39 has secured upon the lower end thereof a 85 crank arm 42, which crank arm is connected by pitman 43 with the vertical frame 34. The lower end of pounder frame 34 is connected by link bar 44 with the upper end of lever 18, and when said frame is moved 90 horizontally said lever is operated to cause the partial rotation of the clothes receptacle through the connecting mechanism before described. Upon the lower end of the pounder shaft is slidably mounted a conical 95 shaped pounder 45, which is open at the bottom. In the top of the pounder and preferably formed integral therewith is plunger chamber 46 which is open at the bottom and is provided with an internal flange 47 100 which supports a spiral spring 48 in said chamber, the upper end of which spring bears against the plunger 49 which is rigidly secured upon the lower end of the pounder shaft 36. If desired the spring could be 105 mounted upon the pounder as shown in dotted lines in Fig. 2.

In the operation of my machine, the clothes with the necessary soap and water, not shown, are placed in the clothes receptacle, the operator grasps the handle 29 and rotates the operating wheel. This motion

through connecting mechanism causes the continuous reciprocation of the pounder in the clothes receptacle. When the teeth 50 at the top of the mutilated gear as shown in Fig. 1, are rotated to engage the bevel pinion, said pinion is revolved a half a turn, the teeth being arranged to effect that motion. This causes the pounder frame 34 to move outwardly to almost the center of the tub. It will be observed that this outward movement of the pounder frame will be effected when the pounder is at the top portion of its reciprocation. At the same time that the pounder frame moves upwardly, the clothes receptacle through connecting mechanism is partly rotated. The next revolution of the operating wheel brings the pounder frame back to the side of the clothes receptacle as shown in the drawings, which motion is effected while the pounder is at the upper portion of its stroke. At the same time the receptacle is partially rotated still farther, thus bringing the pounder to operate upon a different portion of the clothes in the bottom of the clothes receptacle. Each revolution of the operating wheel causes both the shifting of the pounder and the partial revolution of the clothes receptacle so that new portions of the clothes are operated upon until a complete revolution has been made of the clothes receptacle when the further operation of the operating wheel repeats the operation heretofore described. The slot in the shank of the upper frame permits of said frame being adjustable vertically so that the machine can be adjusted for different quantities of clothes which would be usually spread evenly upon the bottom of the clothes receptacle. It sometimes happens that the clothes are not evenly spread or that they gather in bunches in the receptacle. In such cases the pounder would not always come down squarely upon an even surface, but one edge would strike

sooner than the other, and it might sometimes happen it would strike evenly upon a bunch of clothes before the full stroke of the pounder stem was accomplished. In such cases the spiral spring in the plunger chamber would yield and allow the plunger to pass downwardly while the pounder was quiescent. This downward movement of the plunger would force air and water out of the pounder chamber and through the clothes, thereby giving an additional efficiency to the operation of the pounder. It is always preferable in the use of the machine to so arrange the clothes that the pounder will be arrested by the clothes just before the plunger rod has made its full downward thrust so as to cause the plunger to force the air and water out of the pounder chamber through the clothes beneath the pounder.

Having described my invention what I claim is:

1. A washing machine comprising a clothes receptacle; a pounder adapted to reciprocate vertically in said receptacle; means to reciprocate said pounder; means to intermittently and alternately move said pounder toward and from the center of the receptacle.

2. A washing machine comprising a clothes receptacle; a pounder adapted to reciprocate vertically in said receptacle; means to reciprocate said pounder; means to intermittently and alternately move said pounder toward and from the center of the receptacle; and means to intermittently rotate said receptacle.

In witness that I claim the foregoing I have hereunto subscribed my name this 30 day of April 1910.

FREDERICK V. PEPPER.
